UNITED STATES PATENT OFFICE.

HUGO APFELBECK, OF FALKENAU, CZECHOSLOVAKIA.

PRESS FOR MAKING BRIQUETTES.

Application filed October 8, 1926, Serial No. 140,308, and in Germany January 21, 1924.

A known type of rotary press for compressing granular or powdered material is constituted by a ring within which a compression disc is eccentrically mounted, the 5 said disc engaging a groove of the ring. This press has the disadvantage that the length of compressed material to be cut into briquettes (and hereinafter referred to as "the blank") after passing the compression 10 stage adheres to the lateral walls of the annular groove as the material swells, so that certain portions of the blank cannot be entirely stripped off as complete single briquettes; in fact the compressed material is 15 scraped out of the annular groove in pieces.

It has been proposed to avoid this disadvantage by compressing the material between adjacent and oppositely rotating compressing rolls, the compression chamber formed 20 by the space between the rolls being closed laterally by rings bearing on the end faces of the rolls and mounted eccentrically to one of the said rolls, these rings having moreover a larger diameter than the rolls.

25 The free portions of these rings, away from the compression zone, move apart from one another so that the blank jammed between these rings by swelling is first detached from the surface of the rolls and subsequently 30 from the divergently moving rings so that briquettes can be cut from the blank with the aid of the known strippers. This type of press however also has certain practical disadvantages. The blank-conveying rings 35 constituting part of the compression chamber form joints with the walls of the rolls, and since these joints are in the region where the pressure is highest, the material is forced into them, with the result that material is 40 wasted, more power consumed and even the working of the apparatus may be jeopardized.

The present invention aims to remove 45 these disadvantages, and it consists essentially in constructing the grooved ring which forms the compression chamber in two annular sections that rotate in synchronism owing to a positive connection between them, the inner lateral faces of the sections 50 forming the lateral walls of the compression groove, and the floor or bottom of the said groove being formed by a shoulder on one of the said faces fitting a corresponding recess in the other; or both the said faces 55 may be recessed to receive an intermediate ring forming the said floor. The compres-

sion chamber has thus no joints located within the zone of highest direct pressure, and the material remains entirely contained in the chamber. Furthermore, in the press 60 according to the invention, the annular sections of the ring are guided in a direction parallel to the axis of rotation of the said ring so that the lateral walls of the compression groove are at the smallest distance apart 65 at the compression zone, the said distance gradually widening from the front and the rear of the said zone as far as the point at which the blank is stripped off and cut into 70 briquettes.

Another feature of the invention is to form the blank in the groove in two compression stages, i. e. the material is compressed to a certain extent before it reaches the compression disc. This prevents the 75 material from heaping up or accumulating just in front of the compression chamber proper, with the result that the internal resistance of the press is reduced and the 80 briquettes are much more uniform.

A constructional example of the briquetting press according to this invention is illustrated in the accompanying drawings in which

Fig. 1 is a side elevation, partially in 85 section;

Fig. 2 is a section along line $x-x$ of Figure 1;

Fig. 3 is a portion of a similar section shown on an enlarged scale, and 90

Fig. 4 is a fragmental section of a slightly modified construction.

With reference to Figures 1, 2 and 3, the grooved ring consists of two annular sections 9, 10, the inner face of the rim portion 20 of one having a shoulder 7, while the rim portion 21 of the other section has correspondingly shaped recess forming an accurate fit with the shoulder 7. This constitutes the outer closure of a compression groove 2, the lateral walls of which are formed by the lateral inner faces of the annular sections 9, 10. The floor or bottom of the groove 2 is formed by the inner face of the shoulder 7 of the rim 20, the said face being parallel to the axis of rotation of the ring. The joint 8 between the two annular rims 20 and 21 is laterally shifted 105 from the zone of highest direct pressure so that under no circumstances is material forced into the said joint.

In the construction shown in Figure 4,

both the annular sections 12, 13 are recessed to receive an intermediate ring 11 forming the floor of the compression groove. The rim portions 22, 23 of said sections and the intermediate ring 11 are positively connected to one another by means of pins 19. Joints 24 formed by the abutting faces of the said rim portions and of the intermediate ring 11 are laterally removed from the compression groove so that in this case also the material cannot force its way into the said joints.

A roll or rolls 5 located in front of a compression disc 3 preliminarily compresses the material fed from a hopper 4 to the groove 2 so that the said material is fed to die 3 in the shape of a strip or blank 6 which is given its final shape in the region or zone 7 of highest pressure.

20 The annular sections of the grooved ring are guided by rollers 16 and 17 disposed at right angles to the plane of the ring so that the inner faces of the ring sections form, at the compression zone, a groove the section of which is that of the final blank, the width of the said groove gradually increasing as usual both in advance of and behind the said zone towards the point where the briquette is stripped off, so that the finished blank is 25 kept clear, in the customary way, of the lateral walls of the groove 2. The blank is taken out of the groove with the aid of a stripper 14 and drops into a discharge trough 15.

30 The guide rollers, or certain of them, can also be used for moving in the usual way the annular sections 9, 10 of the ring apart from one another in front and at the rear of the compression zone towards the point at which the briquette is stripped off. According to the invention rollers 16, 17 have lateral flanges at their ends between which fits the peripheral portion of the ring. The annular sections of the ring are guided along 35 a predetermined path against the action of the pressure. The roller 16 gives the groove 2 the width of the final blank while the roller 17, which is disposed diametrically opposite the roller 16, has a wedged-shaped 40 collar 18, whereby the faces forming the joint 8 are moved away from one another.

45 As shown in the drawings, one of the driving rollers 1 may also be shaped as a guiding roller, and may comprise two separate parts or members which may be axially adjustable for compensating wear. The pressure exerted at right angles to the annular sections may be taken up also by rollers turning in contact with the peripheral face 50 of the annular sections.

55 Without departing from the invention, the ring may be arranged to revolve about a vertical axis. In this case the pressure rollers likewise rotate about vertical axes.

What I claim is:

1. A briquetting press, comprising a revoluble ring embodying two coordinate annular sections arranged face to face and conjointly providing between the adjacent inner faces of their rim portions an annular compression groove; means for feeding material to the groove; and a rotary compressing disc mounted within and eccentrically of said ring and projecting conformably into said groove, said sections having radial abutment joints which are disposed to one side of the plane of the groove to prevent material from being forced into the joints from said groove during compression.

2. A briquetting press, comprising a revoluble ring embodying two coordinate annular sections arranged face to face and conjointly providing between the adjacent inner faces of their rim portions an annular compression groove; means for feeding material to the groove; a rotary compressing disc mounted within and eccentrically of said ring and projecting conformably into said groove; and means for automatically moving the ring sections laterally away from and toward each other at certain points in the rotary travel of the ring.

3. A briquetting press, comprising a revoluble ring embodying two coordinate annular sections arranged face to face and conjointly providing between the adjacent inner faces of their rim portions an annular compression groove; means for feeding material to the groove; a rotary compressing disc mounted within and eccentrically of said ring and projecting conformably into said groove; and a roller engaging the periphery of the ring and having a circumferential collar of wedge-section which is adapted to project between the said adjacent faces of the ring sections to force the latter apart.

4. A briquetting press, comprising a revoluble ring embodying two coordinate annular sections arranged face to face and conjointly providing between the adjacent inner faces of their rim portions an annular compression groove; means for feeding material to the groove; a rotary compressing disc mounted within and eccentrically of said ring and projecting conformably into said groove; and a plurality of guiding and driving rollers engaging the periphery of the ring at different points, one of said rollers having a circumferential collar of wedge-section which is adapted to project between the said adjacent faces of the ring sections to force the latter apart.

5. A briquetting press, according to claim 4, in which at least one roller consists of two parts which are adjustable longitudinally with relation to each other to compensate for wear.

6. A briquetting press, comprising a rev-
oluble ring embodying two coordinate an-
nular sections arranged face to face and con-
jointly providing between the adjacent in-
5 ner faces of their rim portions an annular
compression groove; means for feeding ma-
terial to the groove; a rotary compressing
disc mounted within and eccentrically of said
ring and projecting conformably into said
groove; and a roller within the ring located 10
in advance of said disc for subjecting the
material to a preliminary compression.

In testimony whereof I affix my signature.

HUGO APFELBECK.
